TANK FOR WATER CLOSETS, URINALS, AND THE LIKE

Filed Feb. 11, 1922

Patented Oct. 4, 1927.

1,644,622

UNITED STATES PATENT OFFICE.

EARL G. WATROUS, OF CHICAGO, ILLINOIS.

TANK FOR WATER-CLOSETS, URINALS, AND THE LIKE.

Application filed February 11, 1922. Serial No. 535,673.

5 Closet tanks have usually been constructed so that they project from the wall above the closet and consequently take up considerable space as well as being more or less unsightly in appearance. The present invention relates more particularly to a tank which may be mounted in a recess in the wall or partition and which will be substantially concealed.

10 The objects of this invention are to provide a new and improved tank of the character indicated and means for mounting the same; to provide a closet tank which may be mounted in a recess but which will be 15 readily accessible; to provide a closet tank which may be mounted in a recess or opening in a wall and which may be swung outwardly to expose the working parts; and in general to provide such an improved construction as will be described more fully herein-after.

In the accompanying drawings showing a preferred form of this invention,

20 Figure 1 is a vertical side view of a tank and closet with parts shown in section;

25 Figure 2 is a sectional view taken on the broken line 2—2 of Figure 1;

30 Figure 3 is a detail showing a telescoping stop and locking member; and

35 Figure 4 is a view similar to Figure 3 showing the parts in engaging position.

The closet 5 may be of any ordinary or preferred form of construction but is shown as a wall closet and is mounted on the face 35 of the wall or partition 6. This closet has an intake pipe or coupling 7 which is shown in the form of an elbow with one branch projecting upwardly. This branch has an outwardly extending flange 8 at the top upon

40 which is placed a gasket 9 which may be held by a clamping ring or clips 10 and bolts 11 or in any other suitable manner. The ring 10 preferably has upwardly extending guides or projections 42. This construction forms a

45 socket for the lower rounded or semi-spherical end 12 of a pipe 13 which is secured to the tank 14 and forms the discharge outlet therefor. The joint between the pipes 7 and 13 makes a tight closure between these 50 parts and at the same time serves as a ball and socket joint upon which the tank may be swung.

55 The tank 14 is preferably made somewhat narrow so that it may be fitted in a narrow opening or recess 15 in the wall or partition 6. The front 16 of the tank 14 is preferably

shaped so as to give an ornamental appearance and has a projecting flange 17 which fits against the wall around the opening 15.

Suitable means are provided for holding 60 the tank in normal position and in the present instance such means comprises a telescoping device such as shown in Figures 3 and 4. A bracket 18 is secured to the wall 19 at the back of the opening and has a rod 20 pivoted 65 thereto. A tube 21 has a bushing 22 at one end with a hole through which the rod 20 passes. A nut 23 is adapted to engage with the bushing to prevent these parts from becoming disconnected. A plug 24 is secured 70 in the opposite end of the tube 21 and has a threaded hole 25 for receiving the threaded end of the rod 20. The plug 24 is provided with a slot 26 or other means whereby it may be readily turned by means of a screw driver 75 or other suitable device. The tube 21 passes through a plate 27 on the flange 17 and the plug or nut 24 projects a sufficient distance beyond the tube to hold the parts together. When the tank 14 is swung upwardly into 80

normal position as shown in Figure 1 the nut 24 is turned until it engages with the end of the rod 20 and thereby serves to hold the tank in position. When it is desired to swing the tank outwardly as shown in dotted lines 85 in Figure 1 to give access to the operating parts, the nut 24 is loosened and the tank is swung out until the telescoping tube and rod reach the limit of their movement as shown in Figure 3 which holds the tank in open 90 position. The tank may be guided in this swinging movement by the sides of the opening as well as the telescoping device, or other guide members may be provided if desired.

95 The water supply pipe 28 is arranged on the center line or axis of the joint between the discharge pipes and is connected by a swinging joint 29 to the pipe 30 which leads to the top of the tank 14 and is connected 100 by a pipe 31 with a downwardly extending pipe 32 such as usually used for filling purposes, and any suitable automatic controlling device for the filling and discharging may be utilized as such devices form no part of 105 the present invention. However, as forming a part of such mechanism the pipe 32 has a valve 33 which is controlled by the float 34. The outlet pipe 13 is closed by a valve 35 which has an upwardly extending rod 36 110 connected by means of a link 37 with a lever 38 which is pivoted at 39 to a plate 40 se-

cured to the flange 17. The lever 38 is operated by a push button 41 which projects out through the plate 27.

From this description it will be seen that I provide an improved tank construction which will occupy practically no space in a room and which will have a pleasing appearance or if desired may be substantially concealed. Furthermore the tank may be protected in the recess and will require no top so that by swinging the tank outwardly all of the operating parts are exposed which is a particularly desirable feature in case of adjustment or repair. Furthermore the device may be easily installed and when connected with a wall closet as shown in the drawings none of the connections or pipes need to be exposed.

It will also be noted that the tank may be made of various shapes and sizes for different installations and the details of construction may be changed without departing from the essential characteristics of the invention and therefore I do not wish to be limited to the exact construction shown and described further than as set forth in the following claims, in which I claim:

1. The combination with a wall having a recess therein for receiving a flushing tank, of a tank adapted to fit in said recess, means for mounting the tank within said recess and means for moving the tank to give access thereto without disconnecting the supply and discharge pipes.

2. The combination with a closet having an intake pipe with a seat in the upper end thereof, of a pipe having its open end fitting in said seat and adapted to rotate therein and be supported thereby, a tank secured to the last named pipe, an outlet valve in the bottom of said tank and means for holding the tank in adjusted position.

3. The combination with a wall having an opening therein, of a tank mounted in the opening and having a flange engaging with the wall around the opening, a jointed dis-

charge pipe for the tank and a stop for holding the tank when it is swung out of normal position.

4. The combination with a wall, of a closet having an inlet within the wall, a tank fitting in an opening in said wall and having an outlet pipe coacting with said inlet to support the tank and permit its being swung outwardly, a bracket, a rod connected with the bracket, a tube fitting over said rod, a stop on the rod to limit the outward movement of the tube, a nut at the outer end of the tube for engagement with the threaded end of the rod, said tube passing through a hole in the tank, and said nut engaging with the tank to hold it in adjusted position.

5. The combination with a wall having a recess therein, of a tank adapted to fit in the recess and having a flange for engagement with the wall, a pivotal support for the tank to permit its being swung outwardly and intake and outlet passageways for the tank arranged to permit the tank to be swung without being disconnected.

6. The combination with a swinging wall tank of a telescoping locking and stop device comprising two telescoping members, means for fastening the members together when in collapsed position and means for preventing the members from becoming disengaged when in extended position.

7. In combination with a wall having an opening, a flushing tank having a pivotal support at the bottom thereof and adapted to swing into and out of said opening and means for holding the tank in normal or other positions.

8. In combination with a wall having an opening, a flushing tank pivotally supported adjacent to the bottom thereof and adapted to have the top swing outwardly through the opening to permit access to the tank, said tank having a front portion of greater width and length than the opening for covering the wall around the periphery of the opening.

EARL G. WATROUS.
